UNITED STATES PATENT OFFICE.

JOHN ALMON MARTIN, OF SOUTH BEND, INDIANA.

DESIGN FOR A SEWING-MACHINE CABINET.

56,703.

Specification for Design.

Patented Nov. 30, 1920.

Application filed May 22, 1919. Serial No. 299,024. Term of patent 14 years.

To all whom it may concern:

Be it known that I, JOHN ALMON MARTIN, citizen of the United States, residing at South Bend, in the county of St. Joseph and State of Indiana, have invented a new, original, and ornamental Design for Sewing-Machine Cabinets, of which the following is a specification, reference being had therein to the accompanying drawings.

This invention relates to the well known type of drop-head sewing machine cabinets

customarily seen in two conditions, viz., open and closed.

The figure is a perspective view of a sewing machine cabinet embodying my new design; the cabinet being closed.

I claim:

The ornamental design for a sewing machine cabinet, as shown.

In testimony whereof I have signed my name to this specification.

JOHN ALMON MARTIN.
